UNITED STATES PATENT OFFICE.

CHARLES K. GILES, OF CHICAGO, ILLINOIS.

WATCH-CASE.

SPECIFICATION forming part of Letters Patent No. 365,987, dated July 5, 1887.

Application filed December 2, 1885. Serial No. 184,534. (Model.)

To all whom it may concern:

Be it known that I, CHARLES K. GILES, a citizen of the United States, residing at Chicago, in the county of Cook and State of Illinois, have invented a certain new and useful Improvement in Watch-Cases, which is fully set forth in the following specification, reference being had to the accompanying drawings, in which—

10 Figure 1 represents a face view of an open-face case embodying my improvement; Fig. 2, a sectional view of the same, taken on the line *xx* of Fig. 1; Fig. 3, a sectional view of the ring-center detached; and Fig. 4, a sectional view similar to Fig. 2 of a modified form 15 of my invention.

Like letters refer to like parts in all the figures of the drawings.

My invention relates to watch-cases, its object being to provide a dust-proof case to inclose the movement and protect the same effectually, while at the same time the movement will be readily accessible for inspection and repair.

25 My present invention is in the nature of an improvement upon the construction set forth in an application filed by me October 22, 1885, Serial No. 180,674.

I will now proceed to describe a construction 30 in which I have practically carried out my invention in one form, and will then particularly point out in the claims those features which I believe to be new and desire to protect by Letters Patent.

35 In the drawings, A represents the case-center. This case-center is provided at its upper edge with an inwardly-projecting flange, *a*, for the purposes hereinafter stated.

40 B indicates a back cap, which may be attached to the case A in any suitable manner, either by snapping or screwing it into place.

In Figs. 1, 2, and 3 of the drawings I have shown a construction in which the center A is internally threaded for a portion of its length, 45 the back cap, B, being provided with a horizontal flange, *b*, and with an externally-threaded cylindrical portion, *b'*, extending above the said flange. In this construction the back cap, B, screws into the threaded center A, the flange *b* forming a seat upon which the center rests when in position, as shown in Fig. 2 of the drawings. This back cap may, however, be

attached in the manner shown in Fig. 4 of the drawings, in which case the center A is shown provided with an externally-threaded projecting flange, *a'*, the back cap being threaded to screw upon the said flange and bear against the center, as clearly shown in said figure.

C indicates a case-lining, which is cup-shaped in form, being preferably constructed in a single piece, and having hinged to its periphery in any suitable manner a movement-holding ring D. This lining is of an external diameter equal to the normal internal diameter of the case-center A, and is adapted to be inserted in the said center from the rear, its front edge bearing against and being supported by the flange *a* of the center, which covers the said edge, as shown in the several figures of the drawings. This lining, when placed in position, may be secured by any suitable means. E represents the front cap of the case, which in the construction shown is hinged to the center A and is provided with the crystal *e*.

In the assembling of the parts composing 75 this case the case-lining C, with its movement-holding ring and movement, is placed in the case-center A from behind, and the back cap, B, is then secured to the case-center, these operations being effected, as desired, either before or after the front cap is applied.

When it is desired to inspect the movement, it is only necessary to remove the back cap and then the lining, when the movement-holding ring may be swung out and the movement 85 thus exposed.

In the construction shown it is obvious that the front cap, E, with its crystal *e*, may be snapped or screwed into position on the center A, instead of being hinged thereto. It is also obvious that the same construction may be applied to a hunter-case watch, the necessary alterations being sufficiently obvious without the necessity of further description. It is also obvious that various modifications in the details 95 of construction may be made without departing from the principle of my invention. I therefore do not wish to be understood as limiting myself strictly to the precise details hereinbefore described, and shown in the drawings. 100

Having thus described my invention, what I claim as new, and desire to secure by Letters Patent, is—

1. The combination, with the center A, hav-

ing inwardly-projecting flange *a* and threaded internally, of the case-lining *C*, having movement-holding ring *D* and adapted to fit within the center and against the flange, the back 5 cap, *B*, having flange *b* and screw-threaded portion *b'*, and the front cap, *E*, substantially as and for the purposes specified.

2. The combination, with the center *A*, having inwardly-projecting flange *a* and a suitable back and front cap, of the cup-shaped 10

case-lining *C*, having movement-holding ring *D*, hinged to its periphery, the said lining being adapted to fit within the case-center and against the flange thereon, substantially as and for the purposes specified.

CHARLES K. GILES.
